UNITED STATES PATENT OFFICE.

WILLARD H. FULLER, OF PASSAIC, NEW JERSEY, ASSIGNOR TO THE SCOVILL MANUFACTURING COMPANY, OF NEW YORK, N. Y.

PHOTOGRAPHIC-PRINTING FRAME.

SPECIFICATION forming part of Letters Patent No. 402,154, dated April 30, 1889.

Application filed October 25, 1888. Serial No. 289,140. (No model.)

To all whom it may concern:

Be it known that I, WILLARD H. FULLER, of Passaic, in the county of Passaic and State of New Jersey, have invented a certain new and useful Improvement in Photographic-Printing Frames, of which the following is a specification.

I will describe a printing-frame embodying my improvement, and then point out the novel features in claims.

In the accompanying drawings, Figure 1 is a back view of a printing-frame embodying my improvement. Fig. 2 is a longitudinal section of the same. Fig. 3 is a view of one section of a tally or record forming part of the printing-frame. Fig. 4 is a view of the forward side of the outer part of said tally or record.

Similar letters of reference designate corresponding parts in all the figures.

20 A designates the frame. It is rabbeted on the rear side, as at a, to receive the glass to be printed from, the paper to be printed, and a cover, B B'. The cover B B' is composed of two sections, the adjacent edges of which 25 are chamfered off, as shown at b b'. These adjacent edges are connected by hinges C, which are of the type ordinarily known as "leaf-hinges." These hinges are shown as having their leaves secured to the front side 30 of the cover-sections by screws or otherwise. Obviously the leaves of the hinges might be secured to the chamfered edges of the cover-sections. The cover is faced on the front side with felt or analogous soft material.

35 One of the cover-sections—in the present instance the section B—has secured to it a stop, D, whereby either cover-section when open may be held in the position into which it is adjusted. This stop may be made of 40 metal, and consists of two sections hinged together, one being secured by screws or like devices to the cover-section B and the other being slotted and connected to the cover-section B' by means of a screw, d, passing through 45 its slot and inserted in said cover-section.

Each of the cover-sections is provided with a securing-spring, E. Such spring consists of a strip of metal bent rearwardly from the middle toward both ends and pivotally connected at the middle to the cover-section to

which it belongs. The ends of each spring 55 coact with concavo-convex catches secured to the sides of the frame. By bending the ends of the springs forward and then swinging the springs upon their pivots they may be disengaged from the catches, so as to release the cover.

On the cover-section B', I have shown a tally or record, G, arranged. It consists of a cup-shaped piece of sheet metal of cylindric 60 form having an internally-screw-threaded hub, g, at the center and a flange at the outer circumference. It is secured in place by tacks or other means passing through it and entering the cover. Its back or circular portion 65 is slotted at regular intervals in a circle and the portions intermediate of the slits are turned up to form ratchet-teeth g'. A disk, g², having figures from 1 to 12, inclusive, marked upon it, preferably by embossing 70 them, is arranged across the open side of the cup-shaped part. A screw, g³, passing through a finger or index, g⁴, and through the disk g² enters and engages with the hub g. The back of the disk g² is provided with a resilient 75 metal strip, g⁵, extended in the form of a circle and adapted to engage with the ratchet-teeth g'. The screw secures the parts in their proper relation and its head exerts friction enough upon the hand or index to keep it stationary. The disk g², having the figures marked upon it, may be rotated, and the strip g⁵ will, by engaging with the ratchet-teeth, secure it in any position into which it may be 80 adjusted, although not with sufficient force 85 to prevent its being adjusted again.

By this construction I produce a very simple tally or record.

In another application, Serial No. 279,376, I show, describe, and claim a printing-frame 90 similar to the one shown and described herein. In this application, however, the frame is provided only to show the connection of a tally mechanism claimed herein.

What I claim as my invention, and desire 95 to secure by Letters Patent, is—

1. A tally for photographic-printing frames, comprising a cup-shaped piece having a screw-threaded hub and the ratchet-teeth turned up from the cup-shaped piece, a disk having 100

figures thereon, a finger, a screw passing through the finger and the disk and engaging with the hub, and a resilient piece secured to the back of the disk and engaging with the ratchet, substantially as specified.

5 2. The combination, with the printing frame, of a tally or record consisting of a part provided with ratchet-teeth g' and an outer part marked with figures and provided

with a spring pawl or detent, g^5 , substantially as specified.

Signed at New York, in the county of New York and State of New York.

WILLARD H. FULLER.
